(57) **CLAIM**

The ornamental design for an anti-snoring pillow, as shown and described.

DESCRIPTION

FIG. 1 is a front, right and top perspective view of an anti-snoring pillow, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 of FIG. 1 thereof. The anti-snoring pillow is shown with a symbolic break in its cord length. The appearance of any portion of the article between the break lines forms no part of the claimed design. The broken lines shown in the drawings illustrate portions of the anti-snoring pillow that form no part of the claimed design.

The dot-dash broken lines depict the boundaries of the enlargements and symbolic breaks that form no part of the claimed design.
